UNITED STATES PATENT OFFICE.

RICHARD FRENCH STONE, OF INDIANAPOLIS, INDIANA.

DESIGN FOR A BADGE.

SPECIFICATION forming part of Design No. 26,376, dated December 8, 1896.

Application filed March 2, 1896. Serial No. 581,587. Term of patent 8½ years.

To all whom it may concern:

Be it known that I, RICHARD FRENCH STONE, a citizen of the United States, and a resident of the city of Indianapolis, county 5 of Marion, and State of Indiana, have invented a new and original Design for Insignia or Badges, of which the following is a full, clear, and exact description.

Figure 1 shows a face view of the design, and Fig. 2 a sectional view of the same to illustrate the relateness of the different features of the design.

The leading features of my design consist in a "spear-pointed" cross 1 of the delineation shown, surrounded by a narrow stripe or border 2 in the center of a circular field 3, said field being surrounded by a double border 5 and 6, and between these borders, in the circular panel marked 4, is provided suitable space for any desired inscription.

The minor features of the design are that all the lines shown in black, as in the drawings, shall in the design proper be of gilt or gold and that the central cross delineation 1 shall be colored red, the circular field delineation 3 shall be colored green, and that the field between the two outer circular borders, delineation 4, shall be black.

Fig. 2 shows a cross-section of the design.

I claim—

The design for a "medical" badge or insignia as herein shown and described.

In testimony whereof I hereunto affix my hand, this 17th day of February, 1896, in the presence of two witnesses.

RICHARD FRENCH STONE.

Witnesses:

W. F. WALKER,
WM. E. STARKEY.
